COMBINATION COAL AND GAS COOKING-STOVE.

1,180,029.

Specification of Letters Patent. Patented Apr. 18, 1916.

Application filed November 9, 1914. Serial No. 871,087.

To all whom it may concern:

Be it known that I, GEORGE W. GRAVES, of Cincinnati, in the county of Hamilton and State of Ohio, have invented certain new and useful Improvements in Combination Coal and Gas Cooking-Stoves and I do hereby declare the following to be a full, clear, and exact description of the same, reference being had to the accompanying drawings, forming a part of this specification, and to the reference-numerals marked thereon.

My present invention has for its object to provide an improved form of cooking stove in which the source of heat, both for heating the top surface and the oven may be obtained, either from fuel such as coal or wood, consumed in the fire-box, or from gas discharged through suitable burners and the invention comprehends an arrangement of parts whereby such economy of space is obtained that an oven of serviceable size is provided, while the cubical dimensions of the body of the stove and the surface area of top are not increased by reason of the dual heating means.

To these and other ends, the invention consists in certain improvements and combinations of parts, all as will be more fully described, the novel features being pointed out in the claims at the end of the specification.

In the drawings: Figure 1 is a front elevation of a stove constructed in accordance with my present invention; Fig. 2 is a rear elevation thereof; Fig. 3 is an elevation of the fire-box end of the stove; Fig. 4 is a view of the opposite end; Fig. 5 is a top plan view; Fig. 6 is a vertical sectional view through the oven, showing the gas burner in inoperative position; Fig. 7 is a similar view showing the gas burner in operative position; Fig. 8 is a horizontal sectional view on the line 8-8 of Fig. 6 including an enlarged scale on the line 9-9 of Fig. 7 including the supply pipe; Fig. 9 is a similar view on the line 10-10 of Fig. 1; and Fig. 11 is a detail horizontal sectional view on the line 11-11 of Fig. 1. 50 Similar reference numerals throughout the several views indicate the same parts.

Heretofore in the construction of combination stoves of this character the difficulty

has been to properly heat the oven chamber both from the fire-box and by means of the 55 gas burners, especially in view of the fact that it is necessary to provide adequate means for also heating a portion of the stove top by the use of gas burners and to allow a suitable location for the accommodation of the gas burner employed for broiling purposes.

Generally stated it may be said that the arrangement of the oven chamber within the walls of the stove casing is such that 65 the products of combustion from the fire-box are carried downwardly at the rear of the stove, beneath the bottom of the oven and upwardly, at the end which is remote from the fire-box, and thence rearwardly 70 where they are discharged into the chimney.

In carrying out the invention I employ a stove having a casing comprising a top 1, a fire-box end 2, an opposite end wall 3, a bottom 4, and front and rear walls 5 and 6, 75 respectively. The oven chamber, shown particularly in Figs. 6 and 7 is normally closed by the door 7 forming a part of the stove casing (Fig. 1) and it comprises the end walls 8 and 9, a bottom 10 and the top 80 formed of the portions 11 and 12 which are arranged in different horizontal planes, the former being slightly higher than the latter and connected thereto by a vertical wall 13. The portion 11 of the oven top, arranged 85 at the forward or fire-box end of the stove, provides a recess in the top of the oven for the accommodation of the burner 14 which is used for broiling purposes.

The top 1 of the stove is divided into the 90 portions A and B, by the transversely extending partition 15 which is arranged above the vertical wall 13 of the oven top. The portion of the stove top at the right hand end of the structure indicated by B 95 may be made of any desired size but in practice I deem it preferable to give it an area of about the same proportion as the part A which is heated directly from the fire-box 16. The top portion of the stove body also comprises a horizontal plate 12* which may be a continuation of the lower part of the oven top 12. This being a step below the higher portion 11 of the oven top provides the deeper space necessary for the accommodation of the several burners 17 employed to 100 105

- supply heat for the portion B of the stove top. The plate 12^a may consist of approximately half of the top of the oven, but in order to provide for the more satisfactory 5 and even heating of this part of the oven chamber, I deem it desirable to provide the latter, in the upper right hand corner, with an offset top portion 12^b which forms a restricted flue 18.
10. The up-draft and down-draft flues of the stove are arranged on the rear of the casing, the down-draft flue being indicated by 19 (Fig. 2), the entrance 20 of which is located above the portion 11 of the oven top 15 while the lower end 21 opens into the circulating flue 22 beneath the oven chamber. The flue 22 is provided with a baffle plate 23 and is in communication with the end flue 24, at the end of the oven, between the walls 20. 5 and 9. Within this end flue are arranged baffle plates 25 and 26 which insure the circulation of the products of combustion into contact with the entire surface of the end 9 of the oven chamber. The up-draft 25 flue into which the products of combustion are discharged and through which they are conducted into the chimney is indicated by 27, the mouth or discharge opening thereof being indicated by the collar 28, to which the 30 usual stove pipe is fitted. From an examination of Fig. 2 it will be observed that the up-draft flue 27 is arranged to cover the larger portion of the space beneath section B of the stove top, and in the rear wall 6 35 which separates these parts is provided a damper 29 which may be opened and closed by an operating handle 30, so that adequate ventilation may be obtained when the burners 17 are in use, this being a provision that 40 is especially desirable when the top B is closed by the usual stove covers. The up-draft flue is also arranged so as to extend into proximity with the recessed top portion of the oven, containing the broiling 45 burner 14, so that when the latter is in operation the fumes may be allowed to escape from the oven chamber directly into the chimney. This is accomplished by providing 50 in the rear wall of the oven an aperture 31 opening into the top of the down-draft flue 19, and in providing the up-draft flue 27 with an aperture 32, adjacent the opening 31, and in further arranging a double 55 damper composed of the leaves 33 and 34 which may be adjusted to simultaneously open both of said apertures. This damper in its normal condition is closed causing the products of combustion issuing from the fire-box to pass downwardly through the 60 flue 19, beneath the oven and upwardly at the end thereof into the up-draft flue 27, but when the damper is in its open position the products of combustion may pass directly from the fire-box into the adjacent 65 end of the flue 27, thence into the chimney

and likewise gas or smoke from the oven may escape through the apertures 31 and 32 into the chimney.

The arrangement of the oven top provides accommodation both for the top burner 17 70 and the broiling burner 14 permitting these to be arranged in juxtaposition and supplied with gas from the single supply pipe 35. The arrangement of the broiling burner at the top of the oven possesses the further 75 advantage that its operation may be easily observed.

I have incorporated in the arrangement of the auxiliary gas burner, employed for heating the oven chamber, the novel feature 80 of so mounting the burner that it may be removed from its operative position within the oven chamber to a position exterior thereof by carrying it beneath a movable portion of one of the side walls of the oven. 85

In the preferred construction of the parts I provide a side wall of the oven with a movable section or panel which may be moved inwardly to provide a space between its lower edge and the bottom of the oven 90 through which the burner may be introduced and which normally occupies a vertical position irrespective of the location of the burner. The panel is provided with lugs or projections which serve as a support for 95 the usual adjustable oven shelf and for the false bottom which is utilized in conjunction with the usual oven bottom. In illustrating this feature of the invention I have shown a burner 40 which is pivoted in the lower bottom corner of the oven and preferably at the end of the latter remote from the fire-box. The pivots are arranged so that the burner when in inoperative position will stand in a vertical position in rear of the line of the 100 end wall 9, in the space provided for the end flue 24 of the stove, and when the burner is to be used for heating purposes it is rotated into the horizontal position above the bottom of the oven. The burner is pivoted 105 at its inner end upon a lug 41 entering the rear wall of the oven while, at its forward end it is journaled upon the inner extremity of the gas inlet pipe 42 which is rigidly mounted in the casing of the stove and is 110 curved so that its outer end is offset beyond the edge of the oven door, as shown particularly in Figs. 8 and 9. The adjustment 115 of the burner is permitted by the movable section or panel 9^a of the end wall 9 of the oven which is preferably hinged, as indicated at 9^b, so that it may be swung inwardly as indicated in dotted lines in Fig. 6. This panel is provided on its inner surface with a series of lugs or projections 9^c in horizontal alinement with corresponding projection 8^c on the opposing wall of the oven, for receiving the ends or edges of the oven 120 shelf. The broiling opening 31 which is utilized in conjunction with the burner 14 125 130

is normally closed and the false bottom, or heat circulating plate 43, which is employed, as shown in Fig. 7, causes an even distribution of the products of combustion when the oven is to be heated by the gas burner 40.

In order to obtain the circulation of heated air within the oven when the burner 40 is used, a side flue 8^a is arranged in the oven wall 8 and in the wall 9 there are provided a plurality of apertures 9^d which are in communication with the flue 24. These apertures, however, are arranged in such a position that the circulation of the air therethrough is prevented when the burner 40 is in inoperative position, a convenient means of accomplishing this object being to locate the apertures in the position shown in Fig. 6, so that the burner will overlie them when it is adjusted into inoperative position exterior of the oven chamber. In order to protect the burner, when in the last mentioned position, against the accumulation of soot carried by the air current through the flue 24, I provide a covering or hood therefor, indicated by 44, which is offset from the oven wall 9 and forms a recess or pocket for the burner. This cover is also provided with a plurality of apertures 44^a coöperating with the apertures 9^d.

The heating of the oven by a gas flame necessitates the introduction of a small proportion of air to support secondary combustion. In the present structure this air is admitted through a passage 45 leading into the bottom of the oven at its forward edge, from an opening beneath the oven door. This passage should be closed when the oven is heated by fuel consumed in the fire-box 16 and it should be opened more or less according to the intensity of the flame emitted from the burner 40 and in order, therefore, to govern the admission of air under these varying conditions, I have provided a sliding damper 46 connected by the arm 47, with the crank 48 on the valve stem 49, which extends downwardly from the valve 50. The latter is supplied with gas from the pipe 51 and is arranged in front of the open end of the intake pipe 42 and the stem 49 being a continuation of the valve handle 52 is oscillated as the valve is opened and closed.

If desired the oven door 7 may be provided with a hook shaped projection 53 which surrounds the handle 52 of the valve in such a manner as to prevent the latter from being accidentally opened, or these parts may be so arranged as to prevent access to the valve handle until the operator has opened the oven door.

I claim as my invention:

1. The combination with an oven casing having one of its walls provided with an opening and a gas burner adjustable through said opening into operative position in the oven, or inoperative position exterior there-

of, of a movable closure for the opening which occupies a position to close said opening when the burner is within the oven.

2. The combination with an oven casing having one of its walls provided with an aperture, a gas burner adjustable through the aperture into operative position within the oven and into inoperative position exterior thereof, of a movable closure for the aperture, shelf supports within the oven some of which are carried on the closure and a heat circulating plate resting on the supports.

3. The combination with an oven casing having one of its walls provided with an aperture, a gas burner adjustable through the aperture into operative position within the oven and into inoperative position exterior thereof, of a hinged closure for the aperture swinging into the oven to permit the adjustment of the burner, shelf supports within the oven some of which are mounted on the closure and a heat circulating plate removably carried on the supports.

4. The combination with an oven having one of its sides provided with a communicating compartment, and a gas burner therein movable into and out of the oven, of a closure for said compartment arranged to permit the movement of the burner into the oven and adapted to close the compartment when the burner is in this position.

5. The combination with an oven having a side wall composed of an upper stationary portion and a lower movable portion, of a gas burner adjustable into and out of the oven beneath the stationary portion of the wall, the movable portion thereof being adapted to occupy its normal position when the burner is within the oven.

6. The combination with an oven having one of its vertical walls composed of a stationary portion and a movable portion and a wall offset from the latter to form a recess, of a gas burner located therein and adapted to be moved into the oven, said movable portion of the wall being arranged to close the recess when the burner is within the oven.

7. The combination with an oven having one of its vertical walls provided with a movable portion and a gas burner adjustable into and out of the oven beneath said movable portion, of a wall offset from the latter and arranged to inclose the burner when it is adjusted into a position exterior of the oven, said vertical wall and offset wall being each provided with ventilating apertures and means on the burner for cutting off the circulation of air through said apertures when the burner is in the inoperative position.

8. The combination with an oven having one of its vertical side walls provided with a swinging panel, hinged at its upper edge, and a gas burner movable into and out of

- the oven when said portion of the wall is swung inwardly, of a wall exterior of the oven arranged to form a pocket for inclosing the burner when in the inoperative position 5 in rear of the panel, said burner and panel being so arranged that the panel may be adjusted, after the burner is moved into the oven, to close the pocket.
9. A cooking stove comprising a stove 10 casing, a fire-box, an oven therein, said casing being formed to provide a down-draft flue at the back of the oven adjacent the fire box, a cross draft flue at the bottom of the oven, an up-draft flue at the rear end 15 of the oven and an outlet for the latter flue in rear of the oven.
10. A cooking stove comprising a casing having a top, a fire-box located beneath and arranged to heat one end portion of the top, 20 gas burners beneath the remaining part of the top, an oven extending beneath both of said portions of the stove top having a top wall provided with a portion offset to form an upwardly extending recess beneath the 25 fire-box-heated-portion of the stove top and a gas burner arranged in said oven recess.
11. A cooking stove comprising a casing having a top, an oven located in the casing having a top spaced from the top of the 30 casing, and comprising right and left hand portions arranged at different elevations and forming a recess in the oven, a transverse wall between the oven top and stove top dividing the latter into separate parts, a 35 fire-box heating one end of said stove top and the oven, a gas burner for heating the other end of the stove top and a separate gas burner accommodated in the recess in the top of the oven.
- 40 12. In a cooking stove, the combination with a casing comprising a top, a fire-box arranged beneath one end thereof, an oven adjacent the fire-box having a top of two parts of different elevations spaced from 45 the stove top, the higher portion being adjacent the fire-box and forming a recess in the oven, of a transverse wall closing the space between the oven and stove top, a gas burner located beneath the stove top and 50 over the lower portion of the oven top and a gas burner also arranged in the recess in the oven.
13. A cooking stove comprising a casing 55 embodying a top, an oven therein and a fire-box at one end thereof, a partition between the oven and stove top dividing the latter
- into a fire-box-heated-portion and an unheated portion, a flue plate located between the oven and the unheated portion of the stove top and arranged to form a restricted 60 flue over the portion of the top of the oven in rear of the partition said stove casing being also arranged to form flues for carrying the products of combustion from the fire-box into contact with the oven and into 65 said restricted flue.
14. A cooking stove comprising a casing, an oven therein and a fire-box at one end thereof, a partition extending transversely between the oven and stove top dividing the 70 latter into a fire-box-heated-portion and an unheated portion, said casing being formed to provide flues for conducting the products of combustion from the fire-box into contact with the oven at its rear side and end, a 75 flue plate disposed above the oven beneath the unheated portion of the stove top and forming a flue of restricted area above the oven in communication with the other flues.
15. A cooking stove comprising a casing, 80 an oven therein and a fire-box at one end of the oven, a partition intermediate the ends of the oven and between it and the stove top, said casing being formed to provide a down-draft flue at the back of the oven, a 85 cross draft flue at the bottom of the oven, and an up-draft flue at the end of the latter, a plate located above the end portion of the oven in rear of the partition arranged to form a flue of restricted area communicating 90 with the up-draft flue at the end of the oven.
16. In a cooking stove the combination with a stove casing having a fire box, an oven in the casing comprising fixed side walls having guides thereon and draft flues 95 for conducting the products of combustion from the fire box into contact with the walls of the oven, of a gas burner arranged at the bottom of the oven, a gas oven bottom adapted to be supported on the guides of the 100 side walls and to coöperate with the latter to form a lower gas heating chamber and an upper baking chamber, one of said side walls of the oven being arranged to provide a circulating air passage connecting said heating 105 and baking chambers of the oven and the other side wall having an outlet leading into one of the draft flues.
